(57) **CLAIM**

The ornamental design for a tire shear band, as shown and described.

DESCRIPTION

FIG. 1 is a perspective view of a tire shear band showing our new design; and,

FIG. 2 is a front view thereof.

The dashed broken lines illustrate structure or features which form no part of the claimed design.

The dot-dash broken lines illustrate boundaries of the claimed design; the dot-dash lines form no part of the claimed design.

The drawings include surface shading, which represents contour and not surface ornamentation.
